[57] CLAIM

The ornamental design for a container, as shown and described.

DESCRIPTION

FIG. 1 is a top and front perspective view of a container showing my new design;

FIG. 2 is a top plan view thereof;

FIG. 3 is a left side elevational view thereof; the right side elevational view being a mirror image thereof;

FIG. 4 is a front elevational view thereof; the rear elevational view being a mirror image thereof;

FIG. 5 is a bottom plan view thereof;

FIG. 6 is a front elevational view of an alternate embodiment of FIG. 1 container;

FIG. 7 is a bottom plan view thereof; and,

FIG. 8 is a top plan view thereof.

The other corresponding views disclosed in an alternate embodiment (FIG. 6) are similar to the first embodiment (FIGS. 3 and 4) except the omission of the outside handles.

FIG. 1

FIG. 2

FIG. 3

FIG. 4

FIG. 5

FIG. 6

FIG. 7

FIG. 8
